UNITED STATES PATENT OFFICE.

JOHN KIRBY, JR., OF DAYTON, OHIO, ASSIGNOR TO THE DAYTON MANUFACTURING COMPANY, OF SAME PLACE.

LAMP.

SPECIFICATION forming part of Letters Patent No. 314,250, dated March 24, 1883.

Application filed July 5, 1883. (No model.)

To all whom it may concern:

Be it known that I, JOHN KIRBY, Jr., of Dayton, Ohio, have invented a new and useful Improvement in Lamps, of which the following is a full, clear, and exact specification, reference being had to the accompanying drawings, forming part of this specification, in which similar letters indicate the same parts, and in which—

10 Figure 1 is a section through reservoir and cast ring A, showing (a) attachments of main support to the cast rings A and G and (b) the attachment of lamp proper and lifting-rod. Fig. 2 is a section through lamp, showing its 15 attachments to lifting-rod A' and to air-conduit B; Fig. 3, plan of cast ring A and part of cast ring G, showing supporting-feet m^9 and air-conduit. Fig. 4 is a sectional view of binding arm and hanger, showing attachments to 20 brace-ring G and cast ring A. Fig. 5 is a section of cast ring A at $x^5 x^5$, Fig. 3. Fig. 6 is a perspective view showing manner of attachment of conduit B to cast ring A. Fig. 7 is a section of brace-ring G at $x^6 x^6$, Fig. 3. Fig. 25 25 8 is a plan of conduit B, showing how its cover C forms part of cast ring A. Fig. 9 is a section through conduit B, on line $x^7 x^7$, Fig. 8, showing cast ring A, lifting-rod A', and fastening-screw d' in elevation. Fig. 10 is a perspective view of cover of conduit B. Fig. 11 30 is a cross-section of cover C on line $x^9 x^9$, Fig. 10. Fig. 12 is a horizontal section in line $x^{10} x^{10}$, Fig. 2, showing cylindrical end of conduit B and vertical cylinders of lamp in position; 35 also the cover C, abutting against air-chamber cylinder M'. Fig. 13 is a section through conduit B on line $x^8 x^8$, Fig. 12, showing its cylindrical end air-chamber cylinder, M, in elevation. Fig. 14 is a vertical section through 40 valve and valve-seat in bottom of oil-reservoir K, Fig. 1. Fig. 15 is a horizontal section on line $x^{12} x^{12}$, Fig. 14. Fig. 16 is a plan of lower side of ring u. Fig. 14, showing under side of valve-seat. Fig. 17 is a plan of rubber ring 45 R. Fig. 18 is a cross-section of rubber ring R. Fig. 19 is a vertical section through side of oil-reservoir K, brace-ring G, and cast ring A, showing lifting-rod A' in position. Fig. 20 is a plan of notch in plate H, showing lug x on 50 reservoir. Figs. 21, 22, and 23 are views of retaining device B'. Fig. 24 is a plan of ring

F'. Fig. 25 is a perspective view of ring F', with its means of attachment of lifting-rod A'. Fig. 26 is a section through chimney-holder, burner-cap, burner-plate, burner-cylinders, 55 and their coupling devices. Figs. 27 and 28 are perspective views of rings G' and H' and cylinder M', coupled and uncoupled. Fig. 29 is a plan of hurricane-cap, showing division-plates. Fig. 30 is an elevation of the lamp 60 complete, one of the lamp-burners, with its shade, being elevated to permit the wick to be trimmed. Fig. 31 shows the shade alone elevated to permit the removal of the chimney. 65

My invention relates to lamps, and more especially to lamps that are adapted to be used in railway-cars.

My invention is designed to furnish a lamp for railway use the oil-reservoir of which may 70 be readily detached for filling without taking down any other part of the lamp. The lamp, further, is provided with means for raising the shade-holder without necessarily moving any other part of the lamp, and for raising the 75 shade-holder, with the shade attached, the chimney-holder, and burner-cap together, if that be desired, as it may be in lighting the lamp or trimming the wick, without moving any other part of the lamp. 80

The construction of my lamp with these objects in view is as follows: To a cast ring, A, Figs. 1^a, 1^b, and 3, having the air-tube, arms B, bosses a a, furnished with internal screw-threads, the flanges b and c on its upper and 85 near its upper edge, and turned out or cast with a recess, so that there shall be a flange, d, at its lower edge, a cylinder, D, which receives and forms an air-chamber around the lower end of the reservoir, is attached by securing, by solder or otherwise, its lower edge to the flange c. This cylinder D has the air-openings e e immediately above its lower edge. To the inner side of the cylinder D, above the air-openings e e, is secured the plate f, open 90 at the center. To a flange on the interior edge of plate f is secured by solder or otherwise an oil-holder, E. The sides of the oil-holder E project above the plate f, and are turned or crimped over an elastic ring, (shown in the 95 drawings, Figs. 17 and 18, as a rubber ring, R, having the flange r,) which they hold in place. 100

The function of the rubber ring is to prevent the overflow of oil out of the holder E when it is violently moved by the jolting of the ears.

5 The oil-holder E is at its bottom secured to plate h, furnished with an internal screw-thread. A stem, k, screws into the plate h, and is also furnished with an internal screw-thread. An ornamental bottom piece, l, fits 10 into the recess or turned-out bottom edge of ring A at flange d, and its bottom is perforated to admit of the passage of the screw-piece m, which sets closely up to the bottom of the stem k. By means of the screw-piece m the ornamental bottom piece, l, and the stem k, with its 15 attachments, are firmly connected.

A cylinder, F, fitting inside of flange b of ring A, is secured at its upper edge to a cast brace-ring, G. It will be seen that there is 20 an air-space, n, between the cylinders D and F, and that the cylinder D is of less diameter and less length than the cylinder F. I do not limit myself to any fixed relative length of cylinder D. The air to support the combustion 25 of the lamp passes from the space n through the holes e e in the cylinder D, and then through the conduits B to the burners.

A plate, H, having air-openings h' h' and open at the center to admit of the entrance of 30 an oil-reservoir, K, is secured to the brace-ring G at its upper edge. The outside edge of plate H is turned down to form a light flange which fits into ring G. If the upper edge of cylinder F is continued and firmly 35 united to the plate H, to form a ring, the ring G may be dispensed with; but I prefer the construction with the ring G. The object of the ring is to stiffen and strengthen the lamp, and it, with the ring A and the rods m⁴, constitutes 40 a rigid frame.

The oil-reservoir I use is made as follows: It is of the student-lamp type, and is of a diameter somewhat less than the diameter of cylinder D, and consists of a cylinder, K, having 45 a top plate, p, raised at one place, p', to make an air-space above the top of an air-tube within the reservoir, and perforated in another place to admit the passage of an air-tube, and having its side projected beyond the 50 plate p to form a cap, p''. This cap p'' is perforated near the top for the admission of air. The reservoir K has an outside flange, q, near the top, which flange rests upon plate H, and serves as a support for the reservoir when in 55 place. The reservoir K has a bottom plate, s, open at the center, and secured to the inner sides of the cylinder of the reservoir at any suitable distance from its bottom edge. The interior edge of the bottom plate, s, is secured 60 to a cylinder, t, and said cylinder t is secured to a ring, u, having an interior screw-thread cut on it. An air-tube, V, passes through the ring u, Fig. 14, to which it is secured, and projects upwardly within the reservoir and into 65 the air-chamber formed by the raised part p' of the top plate, p. Another air-tube, W, also

passes through the ring u, to which it is secured, upwardly within the reservoir through the top plate, p, and into the cap p''. By means of the tube W air passes from the cap p'' to 70 the oil-holder E; thence through tube V to the top of the oil in the reservoir, the raised part p' of the plate p always forming an air-chamber, however full the reservoir may be. It will be seen that there is an air-space between 75 the oil-reservoir K and the outer cylinder, F, (marked in the drawings n',) and also a lesser air-space between the reservoir and the cylinder D, (marked in the drawings n'').

The oil-reservoir K has lugs x x, which fit 80 into openings x' in plate H, Figs. 1 and 19 and 20. These lugs serve, when they are turned under the bottom edge of plate H, to hold the reservoir from rising by the action of the spring z³ on the valve-stem z or from the jolting 85 of the ears. A strengthening-band, x² x², Figs. 1, 19, and 20, may be thrown around the cut-outs or openings x' in plate H.

My valve arrangement fixed in the bottom of the reservoir K, through which oil is admitted to the reservoir, and through which it is fed to the wick, is made as follows: The valve-seat L, Figs. 1 and 14, consists of a cast ring having an interior flange, y, adapted to receive a valve. This ring has a screw-thread 90 cut on it exteriorly, and is adapted to screw into the ring u. From its lower edge the ring of the valve-seat has an extension, y', preferably cylindrical, so that it may serve, when the reservoir is held upside down, as an oil-cup. From the upper edge of the valve-ring two stems or standards, y² y², Figs. 14, 15, and 16, project. A cross-bar, y⁴, perforated at the center to admit of the passage of a valve-stem, is secured to the standards y² y². Another 100 cross-bar, y⁴, perforated at the center to admit of the passage of a valve-stem, is attached to the sides of the cylindrical extension y'. Through these cross-bars passes a valve-stem, z, of the valve Z, Figs. 14, 15, and 16. The stem z has a notch, z', cut in it on one side, below the valve, and has also a thumb-piece, z'', near its lower end.

When the reservoir is to be filled, it is to be turned upside down, and by pressing on the 115 thumb-piece z'' the notch z' may be brought down to the cross-bar y⁴. When in this position, stem z may be pressed to one side to admit the oil. The stem z is fitted with a spiral spring, z³, above the valve Z. This spring z³ 120 abuts against the cross-bar y⁴, and serves to press the valve down on its seat when free to do so. When, however, the reservoir K is in position, the lower end of the valve-stem z rests on the bottom plate, h, of the oil-holder 125 E, and the valve Z is thereby held above the valve-seat to any suitable distance.

The cast ring A, Figs. 1, 2, 3, 6, 8, 9, 12, and 13, has, as shown in the drawings, as integral parts of the casting, tubular air-conduits 130 B. These conduits may, however, be of other material and otherwise attached. These con-

duits are at their outer ends cylindrical, as shown in Figs. 3 and 12, to receive the cylinders of the burner, as shown at Fig. 2, to which they are secured, but may be of any form to suit the chambers they receive. Where these conduits join the ring A said ring is cut away, as shown in Fig. 6, and the upper side of said conduits are also cut away, and are fitted with covers C, as shown in Figs. 1, 2, and 3. The 10 cover C, Fig. 10, has flanges c' and c'' at its inner end, corresponding in every respect to the flanges b and c of the ring A, which serve as continuations of the flanges b and c when the cover is in position. The cover C has also on 15 its upper face a flanged receptacle, c'', to hold a card of directions for the instructions of the handlers of the lamp. The cover C at its outer end abuts against the cylinder of the burner and conforms to its shape.

20 An oil-conduit, M, Figs. 1 and 2, leads from the inside of the oil-holder E through the air-conduit B to the oil and wick cylinder L' of the burner.

The conduits B and covers C are perforated 25 by a hole, a² and a³. (Shown in the drawings, Figs. 3, 8, 9, and 10, as square for the passage of a lifting-arm, A'; also shown as square in Figs. 1, 2, and 19.)

I now proceed to describe my lifting-rod A', 30 Figs. 1 and 2, and its function.

A lifting-rod, A', passes through the hole a³ in the air-conduit B and the hole a² in the cover C, and through the brace-ring G and plate H. The lifting rod A' is fitted at its 35 lower end with a device, B', Fig. 21, for retaining the rod, when elevated, by engaging its catch b' with the lower side of the conduit B. This device B', Figs. 21, 22, and 23, consists of a casting, b², having a thumb-piece, b³, screwed 40 to its lower end and studs b⁴ and b⁵ near its upper end and lower end. On the stud b⁴ is pivoted a catching-lever, b⁶, having the thumb-piece b⁷, and on the stud b⁵ is placed a spring, b⁸, which rests against the back of the catching-lever, and tends to force the lever through 45 a slot cut in the side of the lifting-rod A'. This device is inserted into the lower end of lifting-rod A', and when in position the catching projection b' of the lever passes through the side of the rod and rests on an 50 uncut bar-like portion, b⁹, of the cut side as a retaining-support. The thumb-piece of the catching-lever also projects through the side of the rod below the said uncut portion 55 b⁹. This device operates as follows: By pushing on the thumb-piece b³ the rod is lifted until the catching projection b' of the lever b⁶ passes the edge of the bottom side of the air-conduit B, when it is forced by the spring b⁸ to 60 project beyond the line of the side of the rod A', and engages with the said lower side of the conduit B. The rod is thus retained at that elevation. This rod A', as will be more fully pointed out hereinafter, serves to lift the shade-holder, chimney-holder, and burner-cone. 65 The retaining device B' is to be used when the

rod is raised temporarily—as, for instance, in lighting the lamp.

The lifting-rod is held permanently at any height desired by a thumb-screw, d', Figs. 8 and 9, which passes through a screw-thread boss, d'', on the side of the air-duct B, and into the conduit sufficiently far to press against the side of the lifting-rod.

Above the brace-ring G a curved cast piece, 75 C', having a square shoulder, fits into and is firmly attached to the lifting-rod, and is also firmly attached to a shade-holder, D', Fig. 2. I make the lifting-rod thus in two parts, A' and C', as a matter of convenience in construction.

The holder D' shown in the drawings is the one patented to me December 26, 1882, by Letters Patent numbered 269,587. I however now make an improved hurricane jack 85 or chimney-cap, D'', as shown in Figs. 2, 29, 30 and 31. This cap D'' is closed on top, and is perforated, as at f', to permit the results of combustion to escape around the sides, and internally is divided into compartments by 90 division-plates f''. These plates serve to prevent drafts of air from blowing across the top of the chimney through the air-openings f' f', and thereby creating a vacuum, and affecting, if not putting out, the flame of the lamp. 95

The lifting-rod A' also passes through a boss, E', Figs. 1, 2, 24 and 25, on a ring, F', fitted with a thumb-screw, e'. By means of this thumb-screw the ring F' may be held rigidly at any point on the lifting-rod between the brace-ring G and the air-conduit B. This ring is concaved, as at f³, Fig. 3, to receive the edge of the shade D³, and has arms f⁴ f⁵, Figs. 2 and 24, extending toward the center, where they are firmly attached to a 100 cast ring, G'. The ring F' may be dispensed with by attaching the boss E' and thumb-screw e' to one of the arms f⁴. This ring G', Figs. 2, 26, 27, and 28, has exterior flanges g and g² on its lower and upper edges, and notches g³ cut in the flange g², to allow of the passage of the retaining-lugs h², Figs. 26, 27, and 28, of another ring, H'. Parts of a flange having the notch g³ may be substituted for the flange g². 110

To the inside of the ring G' is soldered the chimney-holder g⁴, Figs. 2 and 26, and inside the chimney-holder g⁴ is attached a burner-cap, g⁵. The lower edges of this holder g⁴ and cap g⁵ extend about half-way down the side 120 of the ring G', where they rest, when in position, on a burner disk or plate, K', Figs. 2 and 26, having air-opening k', open at the center, and having an upward flange, k², to receive a wick-tube, to which it is securely attached, 125 and a downward flange, k³, to fit over an oil and wick chamber. This burner disk or plate K' is downwardly flanged on its outer edge, and is adapted to fit into ring G'. 130

It will be seen, first, that when set-screw e', Figs. 1, 2, and 24, is loosened, the lifting-rod A' may be raised without raising the ring F'

and its attachments. In this case the shade-holder D' and shade only will be raised, leaving the other parts of the lamp undisturbed. Second, by securing the ring F' to the 5 lifting-rod, the rod in raising carries with it the shade-holder D' and its attachments and the ring F' and its attachments including the chimney-holder g⁴ and the burner-cap g⁵, leaving the wick-tube undisturbed and exposed, so that it may be readily trimmed or lighted.

In my lamp, in connection with the parts above described, I use a cylindrical oil and wick chamber, L', Fig. 2, which passes through the cylindrical end of air-conduit B, Figs. 2, 15 12, and 13, to which it is secured. This oil and wick chamber L' has a bottom plate, l', furnished with a screw, l², onto which an ornamented bottom spinning is screwed which extends upwardly to the air-conduit B. A 20 drip-collar, l³, fits at its lower edge into the chamber L', next the top thereof, and is of less diameter at its top than at its bottom edge. A wick-tube, l⁴, is secured to this drip-collar and also to the burner-plate K'. The 25 sides of the drip-collar are perforated, as at l⁴, to allow oil that would otherwise accumulate about the burner to re-enter the oil-chamber. An oil-chamber cylinder, M', having a diameter greater than the diameter of cylinder L', so that there is an air-space, n³, between the cylinders, fits into the cylindrical end of the air-conduit B, Fig. 2, its bottom edge resting on the interior flange, l⁵, of the cylindrical end of conduit B. Flange l⁵ encircles the oil and wick cylinder L', to which it is secured. 30 35

The cylinder M' is cut out on the side toward the reservoir of the lamp. The size and shape of this cut corresponds to the size and shape of the cross-section of the air-conduit 40 B, where its tubular part joins onto its cylindrical part or end, as shown in Figs. 2, 9, and 13.

The cast ring G' and the air-chamber cylinder M' are connected securely and closely together by means of a coupling-ring, H', having hooked retaining-lugs h², adapted to go into notches g³ of ring G'. When the lugs are entered into the notches of the ring H', said ring H' is turned until the hooked lugs h² are engaged over and upon the flange g² of ring G'. A screw-pin, h³, Figs. 2, 26, and 28, passes through the ring G' and into a slot, h⁴, in the side of cylinder M'. This slot h⁴ is of sufficient length to admit the insertion of the pin h³, when the retaining-lugs h² are passed up through the notches g³ of the flange g² of the ring G', and also to permit of the turning of the ring G' sufficiently far to bring the hooked lugs h² onto the flange g² into a retaining position. I prefer to use an additional ring N', Figs. 2, 6, 27, and 28, outside of ring H', of rubber or some other non-conducting substance. When the additional ring is used, the pin h³ passes through the rings N' and H' 55 60 65 into the slot h⁴ in cylinder M'.

The cast ring A, Figs. 1^a, 3, and 4, has two

or more bosses, a. These bosses are screw-threaded internally to receive a screw-bolt, m², which passes through a hollow square, m³, screwed into the lower end of the binding-rod m⁴. The binding-rod m⁴ is at its upper end screwed onto a downwardly screw-threaded projection or lug, m⁵, of brace-ring G, and serves to securely bind the brace-ring G and its attachments to the ring A and its attachments. 70 75

The lamp is suspended by the hangers m⁷, screwed onto a screw-threaded projection, m⁶, of the ring G, and having foot-pieces m⁹ secured to them at the upper end by a screw-lug, 80 m¹⁰. The foot-pieces m⁹ are attached by screws to the ceiling of a car or to any suitable support for a lamp. The threaded pin m² has a hole, m¹², drilled through it, for the insertion of a rod by which it may be turned, to be 85 screwed into or out of the boss a.

It will be seen that when the ring H', Fig. 2, is turned so that its retaining-lugs h² are opposite the notches g³ in ring G', and the pin m² and thumb-piece b³ of lifting-rod A' are removed, the cast ring A, with its attachments—viz., the cylinder D, the oil-holder E, the oil-conduits M, the air-conduit B, and all the burner parts below the burner-cap g⁵, Fig. 3—may be taken down and away from the frame 90 of the lamp, leaving the oil-reservoir K and the air chamber cylinder F suspended from the brace-ring G, and also leaving the raising-rod A', with the shade-holder D', ring F', and the ring G', with the chimney-holder g⁴ and burner-cap g⁵ suspended from the brace-ring G. 95 100

By loosening the set-screw e' and placing the ring H' into retaining position relative to the ring G', the ring F', with its attachments, may be taken down with the ring A 105 and its attachments above mentioned.

It will be seen, also, that the air-openings h' in the plate H, Fig. 1, are little exposed to drafts of air, being guarded therefrom by the vertical walls of the plate H. 110

My invention possesses advantages over all other lamps designed for the same purpose with which I am acquainted. Among the advantages I mention the following:

(a.) The air-chamber n, n', and n², Fig. 1, and n³, Fig. 2, and the air-space of ring A, and air-conduits B have an area greater than the area of the openings h' h' in plate H, which are large enough to support combustion. Therefore the air in these chambers will not 115 be exhausted by a sudden disturbance of the atmosphere about the air-inlets. The burner being securely held in position, all the joints of my lamp are practically air-tight, and the flame is sustained by air coming through the 120 opening provided for that purpose. I do not know of any other lamp on the hurricane principle which contains means for rigidly securing the burner parts together, and no other lamp in which such parts are not easily displaced by the jolting of the cars. Such displacement admits air to the flame otherwise 125 130

than through the hurricane-cap, and the lamp is as sensitive to uneven drafts as if no effort had been made to embody the hurricane principle.

- 5 (b.) To cleanse the chimney, to trim or light the wick in other lamps of the same general character as mine, it is necessary to force it up to the chimney spring-holder until its bottom end will clear the cap of the burner. Then, 10 by tipping to one side, it may be drawn down and out; but this practice soon spreads the springs, so that they will not set close to the chimney, and they soon become useless for the purpose for which they are designed. In my 15 lamp the shade-holder containing the spring chimney-top holder D⁴ is raised away from the chimney by raising the rod A', so that the proper tension of the spring-holder D⁴ is never impaired or destroyed.
- 20 Oil is admitted to the oil and wick chamber L' by an oil-conduit, M, leading from the oil-holder E through the air-conduit B. In my lamp the oil-level (shown in the drawings, Figs. 1 and 2, by the line x⁴ x⁴) is kept at a constant height. When the oil-holder E and 25 oil and wick chamber L' are full to the level of a line slightly higher than the line of the bottom ends of the air-tubes W and V, the access of air to the inside of the reservoir is stopped, and the oil thereafter is fed to the holder only so fast as consumed, on the well-known principle of the student-lamp oil-supply.

I am aware that air-chambers around an oil-reservoir are not new, and also that it is not new to divide air-currents by division-plates. I therefore do not claim these elements, broadly.

Having thus described my invention, what I claim as new, and desire to secure by Letters 35 Patent, is as follows:

1. In a lamp, the combination of the brace-ring, G, the plate H, the oil-reservoir K, the rods m⁴, the ring A, and the oil-holder E, substantially as described.
- 45 2. In a lamp, the combination of the cast ring A, the cylinder D, securely attached thereto and having the air-openings e e, the air-cylinder F, the air-conduits B, and the burner-tubes of the lamp, the cylinder receiving the 50 lower end and forming an air-space, substantially as described.
3. In a lamp, the combination of an oil-holder, a valve, an oil-reservoir having a valve-seat, a cylinder surrounding the valve-seat, and an elastic ring encircling the said cylinder and securely held in position by the upper edge of said oil-holder, as set forth.
4. In a lamp of the student-lamp type, the combination of the oil-reservoir K, having a 55 partition, p, to form an air-cap, p², an oil-holder, E, elastic packing-ring R, between the reservoir and holder, an air-tube, W, connecting the air-cap chamber with the holder, and

an air-tube, V, connecting the holder with the upper part of the reservoir-chamber, as set forth.

5. In a lamp, the combination of an air-tube, B, open at top, and a removable cover, C, formed to receive a card, as set forth.

6. In a lamp, a frame for an oil-reservoir, 70 consisting of a brace-ring, G, a cast ring, A, having conduits for air and oil leading to the burner, and the binding-rods m⁴, connecting said rings, in combination with a lifting-rod sustaining a shade-holder and passing through 75 said conduits and the rim of said brace-ring, substantially as described.

7. In a lamp, the combination of a frame for the oil-reservoir, a shade-ring, a burner, and a vertically-adjustable lifting-rod for the 80 shade and ring, the shade-ring adapted to be disconnected from the rod and rest on the burner.

8. In a lamp, the combination of a reservoir-frame, a lifting-rod movably fixed in said frame, and a ring carrying the chimney-holder and burner-cap, movably attached to said rod, substantially as described.

9. In a lamp, the combination of an oil-tube, a drip-collar having perforations and secured 90 to the upper end of the tube, a wick-tube secured to the collar, and a perforated burner-plate seated on the collar and surrounding the wick-tube, as set forth.

10. In a lamp, the combination of a lifting-rod, A', adapted to be moved vertically in guides on the frame of the lamp, a shade-holder, D', rigidly attached to said rod, and a ring, F', sustaining a chimney-holder and a burner-cap and movably attached to said rod, 95 substantially as described.

11. In a lamp, the combination of wick-tube chamber, cylinder surrounding the chamber, a burner-plate and chimney-holder adapted to be removed therefrom, and a coupling secured to the cylinder to engage the burner-plate, as set forth.

12. In a lamp, the combination of wick-chamber L', cylinder M', burner-plate K', chimney-holder g⁴, ring G', having openings 110 g³, and surrounding the burner-plate, and ring H', having hooked lugs h², and surrounding the cylinder, as and for the purpose set forth.

13. In a lamp, the combination, with the ring G' and the cylinder M', having slot h⁴, of 115 the coupling-ring H' and a ring of non-conducting material secured to the coupling-ring by pin h³, as set forth.

The foregoing specification of my invention signed by me this 20th day of June, A. D. 1883. 120
